H. E. PIEH

COTTER PIN PULLER

Filed March 27, 1925

Inventor
Henry Ernest Pieh
By his Attorney
Merle A. Johnson

UNITED STATES PATENT OFFICE.

HENRY ERNEST PIEH, OF WILLISTON, NORTH DAKOTA, ASSIGNOR OF ONE-FOURTH TO GEORGE H. PIEH AND ONE-FOURTH TO LILLIAN M. PIEH, BOTH OF MINNEAPOLIS, MINNESOTA.

COTTER-PIN PULLER.

Application filed March 27, 1925. Serial No. 18,744.

To all whom it may concern:

Be it known that I, HENRY ERNEST PIEH, a citizen of the United States, residing at Williston, in the county of Williams and 5 State of North Dakota, have invented certain new and useful Improvements in Cotter-Pin Pullers; and I do hereby declare the following to be a full, clear, and exact description of the invention, such as will enable others skilled in the art to which it 10 appertains to make and use the same.

My invention has for its object to provide an extremely simple and highly efficient cotter pin puller, and to this end it consists of 15 the novel devices and combinations of devices hereinafter described and defined in the claim.

In the accompanying drawings, which illustrate the invention, like characters indicate like parts throughout the several views.

Referring to the drawings:

Fig. 1 is a perspective view of the improved cotter pin puller;

Fig. 2 is an end elevation of the cotter pin puller;

Fig. 3 is a transverse section taken on the line 3—3 of Fig. 1; and Fig. 4 is a transverse section taken on the line 4—4 of Fig. 1.

The numeral 4 indicates a pair of jaws 30 pivotally connected at 5 and having handles 6 by which said jaws are operated. Integrally formed with the outer ends of the jaws 4 is a laterally projecting relatively sharp bill 7. The inner face of the bill 7 35 extends at right angles to the jaws 4 and its outer face extends obliquely from the point of the bill to the outer ends of said jaws.

The inner faces of the jaws 4 and the bill 7 are recessed at 8 to leave co-acting relatively sharp clamping edges 9. The back of the jaws 4 in respect to the bill 7 is transversely curved to afford a rocking fulcrum 10 and the ends of said jaws are rounded longitudinally in respect thereto to afford a

rocking fulcrum 11 that extends at right 45 angles to the rocking fulcrum 10. The outer face of the bill 7 is transversely rounded to afford a rocking fulcrum 12 that extends obliquely in respect to the rocking fulcrum 11. The clamping edges 9 diverge from the 50 points of the bill sections and then continue along the ends and sides of the jaws 4 to a distance more than half the length of said jaws.

The inner faces of the jaws 4, inward of 55 the clamping edges 9, are further recessed at 13 and provided with co-acting cutting edges 14.

A cotter pin may be pulled by engaging the same with the co-acting clamping edges 60 9 between the rocking fulcrums 10, 11 and 12 and then removed by rocking the tool on any one of said fulcrums; or a cotter pin may be engaged by the co-acting clamping edges 9 directly opposite the rocking fulcrums 10, 11 and 12. It is also evident that the tool may be rocked on the outer ends of 65 its jaws 4 or at the junction of the oblique surface of the bill 7 with the outer ends of the jaws 4. The point of the bill 7 may be 70 inserted into the eye of a cotter pin to pull the same. Many other movements of the cotter pin puller are possible to pull a cotter pin.

What I claim is:

A cotter pin puller comprising a pair of handle-equipped pivotally connected jaws having at their outer ends a laterally projecting relatively sharp bill, the inner faces of the jaws and bill being recessed to leave 80 contacting relatively sharp marginal clamping edges, certain of which extend parallel to the plane in which the opening and closing movements of the jaws take place and certain others of which extend transversely 85 thereof.

In testimony whereof I affix my signature.

HENRY ERNEST PIEH.
